Primary Examiner—Terry A. Wallace*Attorney, Agent, or Firm*—Curtis, Morris & Safford[57] **CLAIM**

The ornamental design for a adjustable measuring container, as shown and described.

DESCRIPTION

FIG. 1 is a top plan view of the adjustable measuring container showing my new design;

FIG. 2 is a left side elevation view thereof;

FIG. 3 is a rear elevation view thereof;

FIG. 4 is a front elevation view thereof;

FIG. 5 is a bottom plan view thereof; and,

FIG. 6 is a perspective view thereof, with the outer housing elevated to a position higher than that in which it is shown in FIGS. 1-5, and also showing the right side of the adjustable measuring container.
